(57) **CLAIM**

The ornamental design for a canopy for electric vehicle charging stations as shown and described.

DESCRIPTION

FIG. 1 is a perspective view of a canopy for electric vehicle charging stations according to the present disclosure.

FIG. 2 is a front view thereof.

FIG. 3 is a rear view thereof.

FIG. 4 is an enlarged, left side view thereof.

FIG. 5 is an enlarged, right side view thereof; and,

FIG. 6 is a top view thereof.

1 Claim, 5 Drawing Sheets
